UNITED STATES PATENT OFFICE.

CLIFFORD A. BARR, OF LINCOLN, NEBRASKA.

CONCRETE MOLD.

1,408,246.

Specification of Letters Patent. Patented Feb. 28, 1923.

Application filed October 9, 1920. Serial No. 415,722.

To all whom it may concern:

Be it known that I, CLIFFORD A. BARR, a citizen of the United States, residing at Lincoln, in the county of Lancaster and 5 State of Nebraska, have invented a new and useful Concrete Mold, of which the following is a specification.

My invention relates generally to improvements in knock-down, adjustable molds for 10 concrete work, and it is particularly designed for use in the construction of concrete beams.

At the present time, in the construction of 15 concrete work, molds are set up or constructed on the ground as the occasion arises, and after the concrete has set the material used in constructing the molds is usually so broken and full of nails that it is scrapped or thrown away with a consequent increase 20 in over-head expense. The principal reason why ready made molds have not been generally used in concrete construction is because none have so far been found to be sufficiently adaptable to different kinds of 25 work, nor sufficiently inexpensive and transportable to warrant the initial outlay in money necessary to provide them as a part of the permanent establishment of a contractor. Furthermore, the body portion of 30 a commercially successful and practical concrete mold must need be renewable and readily repairable as the hard usage to which it is put quickly deteriorates the material of which it is constructed. Consequently the 35 fundamental details of any practical concrete mold must necessarily be the parts which hold the body together, and these must function in a manner similar to a clamp or frame for the members forming the body of 40 the mold.

With the foregoing in view, I have provided a concrete mold, the body of which may be readily renewed or repaired, and the frame or clamping parts of which may be 45 readily dismounted from the body. Furthermore, I have provided a mold frame which is adjustable both vertically and laterally, and which combines the necessary features of durability, strength and inexpensiveness. 50 Furthermore, the frame of the mold may be used to hold timbers together when it is desired to construct a mold on the ground of miscellaneous stock, and this without the use of many nails or the like which generally 55 necessitate scrapping the timber of which

such a mold is constructed after the concrete has set.

To these and other ends, my invention consists in the construction, arrangement and combination of parts described herein- 60 after and pointed out in the claims forming a part of this specification.

One embodiment of my invention is represented by way of example in the accompanying drawings, wherein;

Figure 1, is a perspective view of the mold assembled.

Figure 2, is an end view of the mold.

Figure 3, is a perspective view of one of the bottom supports forming a part of the 70 frame, and,

Figure 4, is a view of one of the side supports.

Like characters of reference refer to like or similar parts throughout the several views 75 of the drawings, in which:

A designates the bottom of my mold body, and B the sides thereof, which are arranged so that their lower edges lie flush with the under face of the bottom.

Disposed at intervals upon the lower face 80 of the bottom A and extending transversely thereacross are a plurality of supporting bars 1 which are preferably constructed of flattened material such as steel or iron and 85 which have openings 2 formed therein through which nails 3 are driven to attach the same to the bottom. Furthermore, the ends of the supporting bars extend a considerable distance outwardly from the sides 90 B of the body and have longitudinally spaced, aligned openings 4 formed therein through which the lower terminal ends of side supports or bars 5 are inserted when the mold is set up.

The side supporting bars 5 are designed 95 to extend vertically from the bottom supporting bars 1 and each has formed in its upper end an opening 6 through which a nail 7 is driven when the mold is assembled to 100 hold the sides in position. It is here pointed out that both the side and bottom supporting bars may be formed of square or T iron, or of any other configuration, should the occasion therefor arise.

As the pressure of concrete mixture is exerted laterally as well as downwardly with respect to the receptacle wherein it is confined, there are provided a plurality of twisted wires 8 extending transversely across 110

the body of the mold between the side supporting bars 5. The parent loops of these wires are situated intermediate their lengths so that certain minor adjustments may be effected by increasing the number of convolutions of the strands thereof when more minute alignment of the sides B is required. As shown, the ends of the wires extend through small openings in the sides and are twisted about the side supporting bars. When the concrete mixture confined in the mold has become set the wires are clipped and the nails 7 withdrawn, whereupon the mold can be dismounted with facility. In the drawings there are shown a pair of transverse supporting beams arranged between the sides of the body, but these are conventional and do not form a part of the mold construction in practice.

20 In setting up the mold, the bottom supports are nailed in position and the sides B are arranged as shown in Figure 1, whereupon the lower terminal ends of the side supporting bars 5 are inserted in the proper holes 4 and the upper ends thereof are nailed to the sides to hold the mold in its entirety assembled. The wires 8 are then strung and twisted after which the concrete mixture may be poured into the mold.

25 While no end pieces or a top piece is described in connection with my mold the necessity may arise for using them as in the case of forming square blocks. In the event a top and ends are required it is my intention to use the conventional type which forms no part of the present invention. It is here particularly pointed out that the side supporting bars 5 are both laterally and vertically adjustable with respect to the bottom supporting bars 1, so that a variety of sizes of bodies may be used in conjunction with the frame herein described. Furthermore, attention is called to the fact that a mold of this character is easily transported and may be fixed in positions which with

the usual molds are quite inaccessible, such as in forming ceiling abutments and extended beam ends.

While in the foregoing, there has been illustrated and described such combination and arrangement of elements as constitute the preferred embodiment of my invention, it is nevertheless desired to emphasize the fact that interpretation of the invention should only be conclusive when made in the light of the subjoined claims.

Having described my invention and its objects with such attention to detail as will thoroughly acquaint one skilled in the art with its construction and advantages, I claim—

1. A mold for concrete comprising a collapsible body, detachable bottom supports for the body provided with openings, detachable side supports for the body receivable through said openings, and said side supports being vertically movable through said openings to accommodate mold bodies of different heights. 65

2. A device of the character described comprising a bottom support for a mold body provided with a plurality of openings, rods constituting side supports for the mold body and adapted for selective insertion through the openings in the bottom support 70 whereby to permit lateral adjustment of the rods with respect to the bottom support to accommodate mold bodies of different widths, said rods being movable vertically through said openings to permit vertical 75 adjustment of said rods with respect to the bottom support to accommodate mold bodies of different heights, and each of said rods provided with an opening for the reception of a nail or screw to hold the same in fixed 80 position with respect to the mold body. 85

In testimony whereof, I affix my signature hereto.

CLIFFORD A. BARR.
